I. H. SMITH.
MAKING MATCHES.

No. 8,066.

Patented Apr. 29, 1851.

UNITED STATES PATENT OFFICE.

I. H. SMITH, OF WOLCOTT, CONNECTICUT, ASSIGNOR TO LEMUEL D. SMITH.

МАCHINERY FOR MAKING MATCHES.

Specification of Letters Patent No. 8,066, dated April 29, 1851.

To all whom it may concern:

Be it known that I, IRA H. SMITH, of Wolcott, in the county of New Haven and State of Connecticut, have invented a new and useful Machine for Making Friction-Matches; and I do hereby declare that the following is a full, clear, and exact description of the construction and operation of the same, reference being had to the annexed drawings, making a part of this specification, in which—

Figure 1 represents a plan of the machine. Fig. 2 represents a longitudinal section. Fig. 3 represents a transverse section 15 through 00 of Fig. 1. Figs. 4 and 5 represent detached views of the vertical cutter, eccentric and mode of action. Fig. 6 represents detached side elevation of the ratchet feed motion on an enlarged scale. Fig. 20 7 represents enlarged representation of the different processes which the timber, in forming the matches, undergoes.

The timber of which the matches are to be made is taken in the form of plank of 25 any thickness from two to six inches, four or five inches being generally found the most convenient thickness. It is first sawed into blocks double the length designed for the matches, then cut into plates of the requisite 30 thickness for a match splint the width, of course, corresponding with the thickness of the plank from which they are cut. These plates are then dipped in melted sulfur or such other preparation as may be used to 35 facilitate the igniting of the splints, in which state they are ready to be introduced into the machine which completes the operation of making them into matches.

I will now proceed to describe the 40 machine and its mode of operation by reference to the drawings.

S. S. is the main, or driving shaft, with its tight and loose pulleys at S, where the moving power is applied, and its fly wheel f. 45 This shaft is driven with great rapidity, some five hundred revolutions per minute. Upon the point z, of the driving shaft, is a round band passing down with a half turn upon the larger part of the pulley P. (Figs. 50 1. and 3.), and from the smaller part of the same pulley there passes another round band to the pulley G, thus giving to the pulley F, and the feeding apron A which passes over it a greatly reduced motion.

55 c, c, c, are iron cleats upon the feeding apron A, about the thickness of a match

splint and at intervals a little greater than the width of the wooden plates above mentioned.

b, is a box with three sides open at the 60 back end, as represented in the drawing (Fig. 1) some eight or ten inches high, six or eight inches long, and of a width just sufficient to admit the length of the plates, having an opening at the bottom of the left side 65 (Fig. 2) just sufficient to allow the apron with its cleats and of course the apron with a single plate between the cleats to pass through. Into this box the plates of wood to be converted into matches are piled to any 70 height that may be desired, and by the motion of the apron, as will be readily seen, each cleat takes a plate from the bottom of the pile and drives it forward between the feeding rolls g, g. In order that the plates 75 may follow each other closely without any intervals between them as they are fed in between the rolls, the bands are so arranged as to move the feeding apron A, somewhat 80 farther than the ratch motion. The pulley G is loose upon its shaft, and connected with it by the spiral z coiled around the shaft. When one of the cleats c, c, c, is against one 85 side of a plate and the other edge of the plate is between the rolls, or pressing against another forward of it which is between the rolls the feeding belt cannot move faster than the ratch. During this time the spiral coils up more tightly around the shaft, and when the cleat, in passing around the pulley 90 V, slips from the edge of the plate, the spring of the spiral throws the feeding apron suddenly forward, bringing the next cleat in contact with another plate, and driving it at once forward to the one before 95 it. The feeding rolls (g, g,) being driven by the ratch feed r, carry the plate forward the width of a match splint at each revolution of the driving shaft. Between the motions of the ratch feed, the vertical 100 cutter k descends, at each revolution of the driving shaft cutting off a splint. This cutter or knife is screwed to an iron or steel plate the ends of which move in mortices in the sides of the frame closely fitted. The 105 plate itself being hung upon arms standing at an acute angle with it and connected with it and with the frame above by hinged joints, and being worked by the eccentric E moves obliquely or in the arc of a circle, as will be 110 readily seen by reference to Fig. 4. By this motion the knife is made to cut the wood

very smoothly. The edge of the knife may either strike into a bed of rawhide fitted into the iron plate over which the match stuff passes, or it may work close by the edge of a steel plate, operating somewhat like shears. 5 The plates, after passing the feeding rolls till they reach the cutter, and likewise the splints, after being cut, are held in position and kept from any upward motion by plates 10 of brass or steel or other metal passing some distance over the ends of them. The splints being thus held and prevented from piling one upon another are shoved forward by the ratch motion something like an inch beyond 15 the knife till they are caught between the belts B, B, passing over the little rod h (Fig. 2) and the grooved cylinder C, which receives its motion from the large pulley D, by means of the belts above mentioned and its 20 surface moves exactly the distance between the centers of two adjacent grooves at each revolution of the driving shaft thus receiving 25 a match splint in each groove. The cylinder is from half to three fourths of an inch shorter than the splints so that both ends of 30 the splints are allowed to project a little beyond the ends of the cylinder. At the ends of this cylinder in the same plane with its axis and at right angles with the same 35 are the small shafts s, s, (Figs. 1 and 2) upon which are the dipping wheels e, e, with a channel or crease turned into the face of each and placed in such a position that the 40 projecting ends of the splints shall pass into those creases. The surfaces of the dipping 45 wheels move exactly with the surface of the grooved cylinder and the bottoms of the wheels are set down into the dishes d, d, (Figs. 1 and 2) which are filled with the 50 phosphorus composition so that the creases come up filled with the composition and the splints are dipped at both end by passing 55 through the creases the wheels being of such a size and being placed so near the inner 60 edges of the dishes that vertical tangents from the inner surfaces of the wheels where 65 they are in contact with the splints shall fall at some distance from the dishes thus allowing the matches after being dipped to pass 70 the dishes without coming in contact with them.

The dipping wheels receive their motion by means of bands from the large pulley D and the intermediate pulley K (as seen in 55 Fig. 2) the other shaft being driven by a cross band from the first. The large pulley D receives its motion from the driving shaft by the means of the worm and gear seen at W (Fig. 1) where a part of the shaft is re- 60 moved and the worm displaced to give a better view of the gear. The splints after being dipped as above described, are carried around to the bottom of the grooved cylinder, where they are cut in two by the circular knife, n (Figs. 2 and 3). They are

then deposited upon the belts B, B, (as seen in Fig. 2) still remaining separated as upon the cylinder and the dipped ends projecting beyond the belts so as not to come in contact with any other substance. In order to give a steady motion to the belts, they are partially supported by a board placed underneath them throughout their whole length. In this way the matches are carried forward to the pulley H which must be 70 at such a distance from the machine as will give them time to dry enough to prevent their adhering upon being brought in contact with each other. For this purpose a distance of some thirty feet may be required. 75 To facilitate the drying heat may be applied by means of steam pipes (if necessary) along the ends of the matches as they move upon the belts. The matches on reaching the pulley H, are held firmly in contact with it by the broad belt L (Fig. 2) till they reach the bottom of the pulley where they are deposited gently and evenly upon a moving platform underneath or in boxes arranged upon such moving platform. Such 80 motion being given to the platform that each box shall be exactly filled. The above 85 description is doubtless sufficient to elucidate every principle involved in the operation of the machine, but I have some 90 modifications of it in contemplation which I will 95 proceed to specify.

In order to secure more perfect precision and certainty in the motions of the grooved cylinder C, and the dipping wheels e, e, I 100 would place the worm and gear at the point M instead of W on the driving shaft, and connect it directly with the grooved cylinder thus driving the grooved cylinder by the gear, and the pulley D by the belts, instead of the reverse as before described, in this case I would make the pulley D smaller, place it further to the right toward the grooved cylinder, and its shaft in the same plane with the shafts s, s, of the dipping 110 wheels. Then instead of using the bands for driving the dipping wheels as represented in Fig. 2, I would drive them by miter gear connected with the two ends of the shaft of the pulley D. 115

Instead of the mode last described it would perhaps be better to dispense with the pulley D, and with all that part of the belts B, B, to the left of the center of the grooved cylinder C (Fig. 2). In dispensing with the pulley D, I would retain simply the shaft upon which it is placed with the miter gear above described for driving the dipping wheels, and drive this shaft by means of an additional worm and gear connected with the driving shaft as seen at W (Fig. 1) and before described. The long belts B, B, would then be used simply for drying the matches and to give them the proper motion. I would substitute in place 120 125 130

of the flanges which hold the circular knife *n* (Fig. 3) two pulleys of sufficient width to carry those belts, and about an inch less in diameter than the knife. I would pass the 5 belts around these pulleys, and connect the shaft *t* upon which they are placed with the shaft of the grooved cylinder by means of gear so arranged that the surfaces of the 10 belts shall move exactly with the surface of the last named cylinder. Then as I have the belts no longer to hold the splints in the grooves of the cylinder I would substitute for them a metallic apron fitted closely to the cylinder and passing from the little roll, *h*, around to the bottom of the cylinder, thus holding the splints in place till they reach the belts, still retaining the roll, *h*, (though 15 without any belts around it) to aid in placing the splints in the grooves. This last I

am inclined to regard as the most perfect 20 mode of construction, as it secures the most exact correspondence between the motions of the grooved cylinder, dipping wheels and belts, not subject to any variation from the slipping or stretching of bands.

25

What I claim as my invention and desire to secure by Letters Patent is—

1. The mode of feeding in the plates of wood by means of the feeding apron with its cleats, spring pulley *F*, and rollers *g*, *g*. 30
2. The mode of separating and dipping the splints by means of the grooved cylinder *C*, cutter *n*, endless bands *B*, and revolving wheels *e*, *e*.

IRA H. SMITH.
